UNITED STATES PATENT OFFICE

2,498,998

KNOCKDOWN DISPLAY STAND

Kenneth D. Mowrer and Charles N. Jackson,
Wichita, Kans.

Application October 6, 1947, Serial No. 778,108

1 Claim. (Cl. 211—125)

1

This invention relates to a knock-down display stand and has for its object to support items in a position for inspection by prospective customers.

Another object is to facilitate the display of wares such as meats and the like in refrigerated show cases and to give the illusion of bulk to the products being displayed.

A further object is to facilitate the shipping of the display stand so that it will occupy but a minimum amount of space during transportation or storage.

The above and other objects may be attained by employing this invention which embodies among its features a pair of side walls, the perimeters of which have identical shapes, a pair of braces adapted to be detachably connected to the side walls to hold the lower edges thereof in spaced parallel relation, out-turned flanges at the upper edges of the side walls, a cover detachably connected to the flanges and extending across the space between the upper edges of the side walls, an inturned flange along the forward edge of each side wall, a rearwardly extending lip at the lower end of each inturned flange, a downturned flange at the forward edge of the cover and a removable panel slidably supported on the lips between the inturned flanges and the downturned flange.

In the drawings,

Figure 1 is a perspective view of a display stand embodying the features of this invention.

Figure 2 is a view similar to Figure 1 showing the front panel removed.

Figure 3 is a perspective view of the front panel,

Figure 4 is a side view partially in section of Figure 1.

Figure 5 is a transverse sectional view taken substantially along the line 5—5 of Figure 4.

Figure 6 is a fragmentary enlarged detailed view illustrating the flanges joining the side walls and the cover.

Figure 7 is a fragmentary enlarged detail view of the lower edge of a side wall, and

Figure 8 is an enlarged fragmentary sectional view through the lower front corner of the device.

Referring to the drawings in detail, this improved display stand designated generally 10 comprises side walls 11 and 12, the perimeters of which are co-extensive. The front and rear edges of the side walls incline upwardly and rearwardly, and formed along the front edge of each side wall is a flange 13, the purpose of which will be more fully hereinafter described. The bottom

2

edge of each side wall is bent upwardly and inwardly as at 14 in Figure 7, and formed at the upper edge of each side wall is a flange 15 which as illustrated in Figure 6 curves outwardly and downwardly to form a longitudinally extending channel 16 the purpose of which will be more fully hereinafter explained. Each side wall is provided near its lower edge adjacent each end with a bolt receiving opening 17 through which

attaching bolts 18 are adapted to extend.

Cross bars 19 are provided adjacent opposite ends with perpendicular extensions 20 which are pierced to receive the attaching bolts 18 when the device is assembled. A cover comprising two parts each designated generally 21 and 22 forming respectively the forward cover section for the device and the rear cover section for the device is provided, and these cover sections each comprise a top plate 23 provided along opposite side edges with downturned flanges 24 the lower ends of which terminate in return bends 25 and upwardly extending flanges 26, the latter being adapted to be received in the grooves 16 formed by the flanges 15 at the upper edges of the side walls. The forward edge of each plate 23 is provided with a downwardly and forwardly inclined flange 27, which serves as a rest for supporting the upper end of a removable front panel to be more fully hereinafter described.

The removable front panel above referred to comprises a substantially rectangular sheet of relatively stiff material 28 of a size to fit between the side walls 11 and 12 beneath the flanges 13. The opposite dimension of the plate 28 is such as to extend from an inturned lip 29 at the lower end of each flange 13 to the upper edge of the respective side wall. If so desired, the plate 28 may be provided on one face with perpendicular prongs 30 upon which the item to be displayed may be impaled. Obviously, if so desired, the plate may be provided with any advertising matter, and in some instances, the plate on the side opposite that from which the prongs 30 project may be supplied with any suitable legend.

During shipment, the parts disassembled will occupy but a minimum amount of space, and when it is desired to set up the device for use, the side walls 11 and 12 are arranged in spaced parallel relation and joined together by the cross bars 19 with the bolts 18 thrust through the openings 17 in the side walls and the apertures formed in the perpendicular extensions 20 of the cross bars. The covers 21 and 22 or either one of these covers alone may be then slid longitudinally along the upper edges of the side walls 11 or 12 with the

extensions 26 received in the longitudinal groove or recess 16 formed by the flange 15. In this way, the cover will serve to hold the upper edges of the side walls in proper spaced relation. With the cover moved to the extreme forward position, the plate 28 may be introduced into the forward end of the device beneath the flanges 13 to extend between the side walls and rest against the forward edge of the foremost cross member 19 and the downturned flange 27 at the forward end of the respective cover. The plate will be held against falling out by means of the lips 29, and with the spikes or pins 30 extending outwardly it is obvious that the merchandise to be displayed may be impaled thereon for inspection by prospective customers.

By the use of the device, a display of merchandise such as meat, cheese or the like may be produced which gives the appearance of mass and at the same time, the bulk of the product on display may be held in reserve as for instance in a refrigerator.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention what is claimed as new is:

A knockdown meat jack comprising a pair of elongated spaced parallel side walls each having an upwardly and rearwardly inclined front edge, an inturned flange extending along each front edge of each side wall, a rearwardly extending lip at the lower end of each flange, an out-

turned flange at the upper longitudinal edge of each side wall, a cover comprising forward and rear separable sections, said sections extending between the upper edges of the side walls, flanges along opposite side edges of the cover sections slidably engaging the out-turned flange at the upper edges of the side walls, a downwardly inclined flange at the forward edge of the forward cover section, a removable transversely extending brace joining the lower edges of the side walls in closely spaced relation to the inturned flanges, a removable panel slidably supported on the lips between the inturned flanges of the side walls, the downturned flange of the cover and the forward edge of the brace, said downwardly inclined flange of the forward cover section supporting the upper edge of the panel, and meat supporting spikes projecting perpendicularly from the display panel.
